UNITED STATES PATENT OFFICE.

LEWIS R. JAMES, OF EDGEWATER, NEW JERSEY, ASSIGNOR TO ALUMINUM COMPANY OF AMERICA, A CORPORATION OF PENNSYLVANIA.

ROLLING-MILL TABLE.

1,367,052.

Specification of Letters Patent.

Patented Feb. 1, 1921.

Application filed October 16, 1919. Serial No. 331,072.

To all whom it may concern:

Be it known that I, LEWIS R. JAMES, a resident of Edgewater, in the county of Bergen and State of New Jersey, have invented a new and useful Improvement in Rolling-Mill Tables, of which the following is a specification.

This invention relates to lifting tables for rolling mills.

10 The objects of the invention comprise the provision of a table adapted to receive small billets of metal from a set of rolls and move them vertically into position to be passed into a second set of rolls. A further object is to provide such a table constructed so that the operator thereof may be carried thereon in relatively fixed position to the lifting table so that during the lifting process he can manipulate the billet, as by turning it by hand to proper position for re- 15 insertion in the second pair of rolls.

20 The drawing shows diagrammatically in vertical section a two pass rolling mill with the lifting table in two positions, with the operator thereon.

25 Tables to move ingots from one level to another in order to pass them from one set of rolls into a second set at a different elevation are not new. But it is believed that such tables so constructed mounted and operated as to permit the operator thereof to remain in fixed relative position with respect to the ingot carried by the table, are new, and that is the function of the present 30 invention.

35 Referring to the drawing, upon a base 1 is mounted a suitable roll frame 2, carrying a primary set of rolls 3, and a secondary set 4, at a higher elevation than the first set.

40 These rolls are suitably mounted in the housing member 5, as will be readily understood by those skilled in the art. Such details are not described herein, because well understood, and not a part of the present 45 invention. To the left of the rolls 3, a feed table 6 is provided with ordinary rollers 7 thereon, to permit a billet to be easily passed into this set of rolls. This set of rolls is rotated as indicated by the arrow

50 at its left.

After passing therethrough the billet 8 moves by gravity down the inclined chute 9, having idle rollers 10 therein, and comes to rest upon the lifting table 11 composed

of a supporting frame carrying idle rollers 55 12 and fixed supports 13, as will be readily understood from the drawings.

The frame 11 is mounted on a truss member 14 which extends from under the table horizontally to the right, supporting a platform 15, upon which an operator 16 may stand. The beam 14 is carried by a supporting frame composed of uprights 17 and cross brace members 18, as indicated in the drawing. This is mounted upon and fixed to a 60 vertical plunger 19, which extends into a piston and is adapted to be hydraulically operated in the ordinary manner of such hoisting devices.

65 After the billet has come to rest on the rollers 12 of the lifting table it may be readily manipulated by the operator by turning it end for end, or otherwise manually adjusting its position, as for example, by aid of a bar 20, as illustrated.

70 The operation of the apparatus is as follows:

75 Billets are introduced into the rolls 3 from the supporting table 6, and after passage therethrough move by gravity onto the lifting table 11, when the latter is in its lower position. As soon as the billet has been received thereon the operator sets in motion the hoisting device (which may be of any suitable type, and is not necessarily limited 80 to the hydraulic plunger shown) to raise the supporting table to the position shown in dotted lines, thus bringing the billets to the proper level to be fed into the upper 85 pair of rolls 4. While the table is in motion, the operator, standing on the platform 15, which is a part of the rigid construction of the entire lifting apparatus, manipulates the billet, so that when the 90 table has reached its upper position the 95 billet is in proper relation to the second set of rolls to be passed thereinto. Thereafter the table is dropped again to receive another billet, and so on. By this apparatus 100 permitting an operator to be continually in the same relative position with respect to the billet which he has to move, his work is very greatly facilitated and expedited.

105 The mill is particularly adaptable for rolling very small billets or those of light weight, as for example, aluminum.

I claim:

1. A lifting table for rolling mills com-

prising a support for the billet, another support attached to the first and forming a platform for the table operator.

2. The combination with a rolling mill comprising two sets of rolls at different elevations of a lifting table adapted to receive billets from one set of rolls and move them to a suitable elevation for passage to the other set of rolls, a platform attached to the

lifting table adapted to support an operator, ¹⁰ and means to raise and lower the combined table and operator support.

In testimony whereof, I have hereunto set my hand.

LEWIS R. JAMES.

Witness:

HOWARD L. SNIVELY.
